[57] CLAIM

The ornamental design for an adjustable file card holder, as shown and described.

DESCRIPTION

FIG. 1 is a perspective view of an adjustable file card holder with the arms in an open position, showing my new design;

FIG. 2 is a side elevational view with the adjustable arms in an upright position, the opposite side being a mirror image thereof;

FIG. 3 is an end elevational view, the opposite end being a mirror image thereof;

FIG. 4 is a bottom plan view;

FIG. 5 is a top plan view;

FIG. 6 is a side elevational view showing the adjustable arms pivoted to an open position; and

FIG. 7 is a bottom plan view thereof with the stand member in an alternate position.

FIG. 1

FIG. 5
